INVENTOR

UNITED STATES PATENT OFFICE.

DUNCAN MCLEAN, OF SPARROWS POINT, MARYLAND.

BUILDING WALL.

Application filed November 19, 1923. Serial No. 675,763.

To all whom it may concern:

Be it known that I, DUNCAN MCLEAN, now residing at 28 Canton Street, Sparrows Point, Maryland, a British subject, have invented a Building Wall.

This invention relates to improvements in building walls.

An object of the invention resides in providing a building wall formed of inner and outer frame members secured in spaced parallel relation and interconnected so that the outer frame will substantially reinforce the inner frame which is constructed to carry the major portion of the weight of the building, while each of the frames are formed of a plurality of horizontal and vertical timbers which receive and have the wall forming surfaces attached thereto.

The invention comprehends other objects in the construction of a wall more particularly pointed out in the following detailed description directed to preferred forms of the invention, it being understood, however, that various other ways may be provided for carrying out the invention within the scope of the invention as herein set forth.

In the drawing forming part of this application;

Figure 1 is a side elevation of one form of the improved wall structure made according to the present invention, portions being broken away to clearly illustrate the various portions of the wall structure.

Figure 2 is a horizontal sectional view of the wall shown in Figure 1.

Figure 3 is a vertical sectional view of the wall shown in Figure 1.

Figure 4 is a vertical sectional view showing the outer and inner wall structures directly attached to one another.

Figure 5 is a horizontal section through a wall portion having the outer and inner wall frames constructed in a similar manner and showing a special spacing member.

Figure 6 is a vertical section through a wall having frames constructed similar to the outer frame secured to both sides of a main frame similar to the inner frame of Figure 1.

Figure 7 illustrates the manner of applying wall plates to the outer frames.

1 indicates the outer frame built up of a plurality of vertical and horizontal frame forming bars which may be either single or double as indicated at 2. The expanded metal 3 is attached to the outer face of this

outer frame and receives the plaster wall forming coating which covers both sides of said metal as indicated at 4 and 5. A suitable finishing coating 10 may be applied to the outer plaster coating 5 to properly finish the outer wall surface.

The inner frame which forms the main supporting structure is composed of a plurality of uprights 6 and 9 which extend between horizontal timbers or bars 7 and 8, the bar 8 forming the sill and the bar 7 forming the horizontal joist receiving member for the floor of the building. The inner wall surface as indicated at 10' in Figure 3 is applied directly to the inner frame by securing the expanded metal receiving the plaster thereto.

Suitable bar members 6' shown in Figures 2 and 3 serve to secure the inner and outer frames in spaced parallel relation in forming the completed wall structure in which the main inner frame forms the main supporting structure while the outer frame substantially reinforces the wall structure and the inner frame in the completed wall and provides an air space for free passage of air between the outer and inner wall faces.

The outer wall may be directly connected or built against the inner wall as shown in Figure 4.

In Figure 5 a construction is illustrated wherein vertical standards 9' having dovetailed edges directly connect the inner and outer wall structures by having the frames forming said structures bolted directly thereto as indicated at 13. In this figure both wall structures correspond in construction with the outer wall shown in Figures 1 and 2.

In Figure 6 a construction is illustrated wherein outer and inner frames are arranged at opposite sides of the upright 6^a and spaced slightly therefrom by the members 14 to which said frames are secured. The use of single slabs to fit within the openings of the outer frame is illustrated at 15 in Figure 7, the edges of the slabs being rabbed to permit the seating of said slabs in the frames.

From the foregoing description it will thus be seen that a wall construction is provided consisting of a pair of frame members of which the inner frame member is preferably constructed of heavier material in order to form the main supporting frame of the

wall. The outer frame further reinforces the inner frame to provide greater rigidity to the finished wall and at the same time provides an air space for free air circulation 5 between the inner and outer walls to reduce heat transmission through the wall.

What is claimed is:

A wall structure for buildings comprising a main inner frame having heavy horizontal 10 timbers arranged at the floor leved for receiving and supporting the floor beams, said horizontal timbers having vertical parallel spaced supporting timbers, the vertical and horizontal timbers being rigidly united to

form a rigid frame structure, an outer frame 15 composed of equally spaced vertical and horizontal frame members rigidly connected together, the frame member of said outer frame being substantially smaller in size than the timbers of the inner frame, connecting 20 members between said inner and outer frames rigidly connecting said frames in parallel spaced relation, the outer frame forming a reinforcement for the inner frame, and covering means for the outer face of the outer 25 frame and the inner face of the inner frame forming finished wall surfaces thereon.

DUNCAN McLEAN.
